UNITED STATES PATENT OFFICE

HENRY HARRISON YATES, OF CREMORNE, NEAR SYDNEY, NEW SOUTH WALES,
AUSTRALIA

CREELING MECHANISM

Application filed May 15, 1929, Serial No. 363,265, and in Australia May 28, 1928.

This invention relates to expanding creel mechanism having adjustable bobbin spindles or pegs for the purpose of withdrawing yarn from cops, bobbins and the like, packed in a confined space, provision being made whereby access is given for quick loading and unloading.

The invention further relates to means for holding a large or small number of yarn ends in a confined space and is adapted to 10 fit behind a narrow or broad loom for the purpose of delivering the warp yarn for weaving; and is adapted for use with any type of cop, or ring bobbin, ring tube, doubler bobbin, doubler tube, or any other form 15 of spun or doubled yarn container.

An object of the invention is to provide a creel mechanism which will enable the process of weaving of yarn to be effected 20 directly from any form in which the yarn is spun or doubled.

A further object of the invention is to provide creeling mechanism whereby a saving in floor space is effected.

25 A still further object of the invention is to provide means whereby the various parts such as spindles, yarn rods, guides, and gates, are interchangeable.

The improved creeling mechanism will 30 hold many times the length of yarn which it is usually possible to get on the weaver's beam of a loom and does, in fact, take the place of such beam.

The creeling mechanism can be expanded 35 or contracted by the addition or reduction of a number of gates without taking up any more floor space, and will accommodate from one to five thousand yarn ends behind a thirty two inch reed space loom and only 40 take up the same width of space as the loom and not more than three feet in depth of floor space. This ratio of space and number of ends can be carried out for any width of loom wider than the above.

45 By giving easy access to individual cops, bobbins or the like the invention enables the worker to either repair, replace or completely reload the creel without stopping the loom for weaving, or unduly disturbing 50 the remainder of the yarn.

A further advantage of the invention is that owing to the main frame being mounted on wheels the whole creel may be replaced by a fresh creel in case of necessity, without stopping the loom longer than 55 is at present required when changing the beam in a loom.

In cases where floor space is unprocurable, the creel may be slung up high above the loom and can be attended to from a 60 raised platform.

The invention includes a main frame, several gates pivotally mounted thereon, a plurality of vertically disposed creel or bobbin supporting bars adapted to slide in the top 65 and bottom members of the said gates, and a plurality of yarn guides, together with clamping means for the creel or bobbin spindles and means such as trolley wheels for rendering the creeling mechanism portable. 70

The main frame is of rectangular shape, and is mounted upon trolley wheels. The upper and lower members, of the frame are slotted to receive pivots which are fastened 75 to the respective gates by plates secured to the side faces of the upper and lower members of the said gates.

Several gates are pivoted to the main frame; each of which has a slotted top 80 member preferably formed by two pieces of angle iron, and a lower member of channelled section, the upper and lower members being connected by vertical members to form a rectangular frame. 85

The bobbin spindle or creel peg supporting bars extend from the upper member to the lower member of the gate and are provided with rollers to facilitate their lateral movement, the rollers being mounted 90 upon transverse spindles carried by a block secured to the upper and lower ends respectively of the bobbin supporting bars. The rollers of each block are not placed in line when viewed in plan but are disposed on 95 their respective spindles one at each end of the block to form a spaced support which prevents the tendency of the supporting bars to assume a position out of the vertical plane, as would be likely to occur were 100

the said bars mounted upon one axially disposed roller or pair of rollers at the top and the bottom of each bar.

The bobbin spindles or creel pegs are clamped to their supporting bars to prevent rotation by means of a slotted member having a thumb screw and split boss in which latter the said spindles or pegs are held. Alternatively the spindles or pegs may be formed with grooves for retaining them in their positions upon the supporting bars by means of a plate having a spring hinge.

Guides for directing the path of the yarn from the cops or bobbins to the usual spacer disposed on or near a loom, are mounted upon brackets secured to each of the supporting bars.

The means for securing the gates against rotation on their pivots may consist of a quadrant having holes through which a pin is adapted to be inserted for engagement after having been passed through the lower member of the gate. The quadrant is removably clamped to the lower member of the main frame by means of a thumb screw.

But in order that the invention may be more readily understood, reference will now be made to the accompanying drawings wherein only such number of gates, bobbin supporting bars, and cops or bobbins are shown as are necessary for clearness and to fully describe the invention; it must therefore be understood that there are a plurality of gates, bars and cops or bobbins according to the quality of cloth being woven.

Figure 1 is an elevational view of the main frame with four gates mounted therein.

Figure 2 is a plan view corresponding to Figure 1.

Figure 3 is a part elevational view showing the upper end of a gate pivoted to the main frame.

Figure 4 is a plan view of one of the gates showing the rollers upon which the upper ends of the bobbin supporting bars are mounted.

Figure 5 is an elevational view partly in section showing one of the bobbin supporting bars, the rollers upon which it is mounted to move longitudinally in the upper and lower members of the gate, and the brackets for carrying the guides for directing the path of the yarn from the cops or bobbins.

Figure 6 is a detail plan view showing the disposition of the rollers and block in relation to their respective bobbin supporting bars.

Figure 7 is a perspective view of a modified means for mounting the bobbins spindles or creel pegs in their supporting bars.

Figure 8 is a view showing one of the bobbin spindles or creel pegs provided with retaining grooves.

Figure 9 is a detail view showing the method adopted for preventing turning of the gates about their pivots.

The main frame 10 is of rectangular shape and has secured to its lower member several transverse shafts 11 upon which trolley wheels 12 are loosely mounted.

The upper member of the main frame 10 is provided with a slot 13 in which is received the upper pivots 14 of the gates 15 said pivots being provided with nuts 16 for tightening purposes.

The lower member of the main frame 10 is similarly slotted to receive the lower pivots 17 of the said gates.

The pivots 14 and 17 are secured to the respective gates 15 by means of saddle shaped plates 18 attached to the side faces of the upper or lower members of the gate as the case may be.

The top member of each gate 15 is preferably formed by two pieces of angle iron 19 spaced to form a slot 20. The lower member 21 of each gate 15 is preferably formed from material of channel section as shown in Figure 5, the frame of the gate being completed by side members 22.

The bars 23 for supporting bobbin spindles or creel pegs extend from the upper member of the gate to the lower member 21 thereof and are provided with rollers 24 to facilitate their lateral movement, the rollers 24 being mounted upon transverse spindles 25 carried by a block 26 secured to the upper and lower ends respectively of the bobbin supporting bars 23. The rollers 24 of each block 26 are not placed in line when viewed in plan (see Figs. 6 and 7) but are disposed on their respective spindles one at each end of the block 26 to form a spaced support which prevents the tendency of the supporting bars to assume a position out of the vertical plane, as would be likely to occur, were the said bars 23 mounted upon one axially disposed roller or pair of rollers at the top and the bottom of each of the bars 23.

The bobbin spindles or creel pegs 27 are clamped to prevent rotation to their supporting bars 23 by means of a slotted member 28 (see Fig. 5) having a thumb screw 29 and split boss 30 in which latter the said spindles or pegs are held. Alternatively the spindles or pegs 27 may be grooved as shown in Figure 8, and retained in their position upon the supporting bars 23 by a plate 31 having a spring hinge 32. (See Fig. 7.)

Guides 33 are provided as shown in Figure 5, or in the modified form as shown in Figure 7, for directing the path of the yarn from the cops or bobbins 34 to the usual spacer disposed on or near a loom and are mounted upon brackets 35 secured to each of the supporting bars 23.

The means for securing the gates 15

against rotation on their pivots 14 and 17 may consist of a quadrant 36 (see Fig. 9) having holes 37 through which a pin 38 is adapted to be inserted for engagement after having been passed through the lower member 21 of the gate. The quadrant 36 is removably clamped to the lower member 21' of the main frame by means of a thumb screw 37' and an extension 38' of the said quadrant.

In use the gates 15 are mounted in the main frame 10 upon their pivots 14 and 17 and are locked in the desired position by the nuts 16, and by inserting the pins 38 in the holes 37, formed in the respective quadrants. The yarn is drawn off the bobbins or cops 34, (see Fig. 2), passes through the guide (Fig. 5 or Fig. 7) and engages with a glass rod 39 mounted upon an edge of the respective gates 15 and then passes through a spacing reed 40 of usual construction.

I claim.

1. A creeling mechanism consisting of a main frame, a number of gates pivotally mounted on the main frame, a plurality of vertically disposed creel or bobbin supporting bars adapted to slide longitudinally in the respective gates, bobbins or cops mounted on bobbin spindles or creel pegs carried by the vertically disposed creel or bobbin supporting bars, and clamps thereon to prevent rotation of said spindles or creel pegs, brackets mounted upon said bobbin supporting bars and guides upon said brackets for conducting yarn from said bobbins or cops.

2. A creeling mechanism consisting of a main frame having transverse shafts upon which trolley wheels are loosely mounted, a number of gates pivotally mounted on the main frame, a plurality of vertically disposed creel or bobbin supporting bars slidably mounted in the respective gates, and movable longitudinally thereon, bobbins or cops mounted on bobbin spindles or creel pegs carried by the vertically disposed creel or bobbin supporting bars, and clamps thereon to prevent rotation of said spindles or creel pegs, brackets mounted upon said bobbin supporting bars, and guides upon said brackets for conducting yarn from said bobbins or cops.

3. A creeling mechanism consisting of a main frame, trolley wheels carried by the main frame for rendering it transportable, a slot in the upper member of the main frame and a slot in the lower member of the said frame, a number of gates, pivoted thereon received in said slot, a plurality of vertically disposed creel or bobbin supporting bars slidably mounted in said gates, and guides for conducting yarn from bobbins or cops mounted on bobbin spindles or creel pegs carried by the vertically disposed creel or bobbin supporting bars, and clamps there-

on to prevent rotation of said spindles or creel pegs, brackets mounted upon said bobbin supporting bars, and guides upon said brackets for conducting yarn from said bobbins or cops.

4. A creeling mechanism consisting of a main frame, a number of gates pivotally mounted on the main frame and having their upper members formed from two pieces of angle iron spaced apart to form a slot; a lower member and side members for each gate, a plurality of vertically disposed creel or bobbin supporting bars slidably mounted in said gates, bobbin or cops mounted on bobbin spindles or creel pegs carried by the vertically disposed creel or bobbin supporting bars.

5. A creeling mechanism consisting of a main frame, a number of gates pivotally mounted on the main frame, a slotted upper member and a channeled lower member for each gate, a plurality of vertically disposed creel or bobbin supporting bars slidably mounted in said gates, rollers carried by a block mounted upon the upper end of each of the creel or bobbin supporting bars and rollers carried by the lower end of the said bars whereby the bars are adapted to slide longitudinally in the respective gates, a plurality of bobbin spindles or creel pegs mounted upon the creel or bobbin supporting bars and guides supported by the bars for conducting yarn from bobbins or cops mounted upon the bobbin spindles or creel pegs.

6. A creeling mechanism consisting of a main frame, a number of gates pivotally mounted on the main frame, a plurality of vertically disposed creel or bobbin supporting bars adapted to slide longitudinally in the respective gates, brackets mounted on the creel or bobbin supporting bars and guides carried by the brackets for conducting yarn from bobbins or cops mounted on bobbin spindles or creel pegs carried by the supporting bars.

7. A creeling mechanism consisting of a main frame, a number of gates pivotally mounted on the main frame, a plurality of vertically disposed creel or bobbin supporting bars adapted to slide longitudinally in the respective gates, brackets mounted on the creel or bobbin supporting bars and guides carried by the brackets for conducting yarn from bobbins or cops mounted on bobbin spindles or creel pegs carried in the boss of a slotted member adapted to be clamped to the said supporting bars.

8. A creeling mechanism consisting of a main frame, a number of gates pivotally mounted on the main frame, a plurality of vertically disposed creel or bobbin supporting bars adapted to slide longitudinally in the respective gates, brackets mounted on the creel or bobbin supporting bars and

guides carried by the brackets for conducting yarn from bobbins or cops mounted on bobbin spindles or creel pegs carried in slots formed in the said supporting bars, and a plate mounted upon spring hinges for retaining the bobbin spindles or creel pegs in the slots in the supporting bars.

9. A creeling mechanism consisting of a main frame, a number of gates pivotally mounted upon the main frame, a quadrant for each gate clamped to the lower member of the main frame, a pin adapted to pass through a hole in the lower member of each gate and engage one or other of a number of holes in the respective quadrants, a glass rod mounted upon one of the side members of each gate, a plurality of vertically disposed creel or bobbin supporting bars adapted to slide longitudinally in the respective gates, brackets mounted upon said bobbin supporting bars, and clamps thereon to prevent rotation of said spindles or creel pegs, and guides upon said brackets for conducting yarn from bobbins or cops mounted on bobbin spindles or creel pegs carried by the vertically disposed creel or bobbin supporting bars.

In testimony whereof I have hereunto set my hand.

30 HENRY HARRISON YATES.
